SLUG CASTING MACHINE

Luther E. Morrison, New York, N. Y., and Frank C. Frolander, Elizabeth, N. J., assignors to Mergenthaler Linotype Company, a corporation of New York

Application September 16, 1933, Serial No. 689,710

34 Claims. (Cl. 199—50)

This invention relates to slug casting machines such as linotype machines of the general organization represented in United States Letters Patent to O. Mergenthaler, No. 436,532, wherein circulating matrices and expansible spacebands are composed in line by the manipulation of a keyboard, the composed line transferred to a slotted mold for the casting of a type bar or slug, and the matrices and spacebands thereafter 10 separated and returned by a distributing mechanism to the magazines from which they started.

In these machines, when the composed line is presented to the mold, it is positioned between a pair of clamping jaws which have previously been 15 set to receive it, and while so positioned, the line is justified by the expansion of the spacebands which are driven up through the line by a so-called justification bar operated prior to the casting operation. Ordinarily, the right-hand jaw 20 is relatively fixed (having only a limited movement to operate the customary pump stop), whereas the left-hand jaw is adjustable to different positions to accord with the length of the mold slot or with the length of the composed 25 line in its justified condition. In casting under such conditions (which are the most common conditions), it is obvious that the number of matrices and spacebands composed must be sufficient to fill out the line completely (except of 30 course for the limited space allowed for justification), and hence when it is desired to cast slugs with blank spaces at the ends for indenting or centering, it is necessary to employ blanks or quads for that purpose, involving considerable 35 annoyance and delay.

It is now common practice to equip the machines with quadding and centering devices which adapt them to handle not only lines of full length as ordinarily, but in addition lines of less than 40 full length (regardless of their actual length), so that the latter lines may be composed without blanks or quads and merely with the matrices necessary for the printed matter. While various 45 schemes of this sort have been proposed, the device disclosed in the co-pending application of Frank C. Frolander, Serial No. 658,077, filed February 23rd, 1933, offers many improvements upon prior arrangements in the way of greater 50 simplicity, better efficiency, and more extended scope of operation, and while capable of wider application the present invention is shown and described as particularly applied to the device disclosed in that application, to which reference 55 may be had for a thorough understanding of the

construction and operation of those parts not shown and described herein in detail.

In the Frolander device, the left-hand jaw is adjustable manually to different set positions for casting lines of different lengths, and the extent 60 of outward movement of the jaw or jaws from their line contacting positions to permit the line to be spread by the spacebands during justification is determined by a cam which is adjusted manually to correspond to the setting of the jaw. 65 Furthermore, a single cam is utilized for this purpose, whether only one jaw is used, as in quadding, or both jaws, as in centering.

As one feature of the present invention, the adjustment of the left-hand jaw for a line of given 70 length is utilized for automatically (instead of manually) determining the extent of the maximum outward or line-spread movement of the jaw or jaws during justification for that particular length of line.

As another feature of the invention, two cams (instead of one) are provided for determining the extent of the outward or line-spread movement of the jaw or jaws. These cams (which are of different eccentricity) are located on a 80 bushing which is shiftable automatically to bring one or the other of the cams into operative position, according to whether the device is conditioned for quadding or for centering. The bushing is also rotatable and connections are provided between it and the left-hand jaw, whereby the manual adjustment of the jaw rotates the bushing and turns the cam in use into position to determine the proper amount of spread for a 85 line of the given length which the jaws are set 90 to receive. The connections between the cam bushing and the left-hand jaw are such that subsequent movement of the jaw into line contacting position for quadding or centering (when the line will of course be of less than the given 95 length) has no effect whatever on the bushing or cams, the latter being free to be automatically operated in reducing the amount of line spread in a manner similar to that set forth in the Frolander application referred to.

These and other features of the invention will be fully set forth in the detailed description to follow.

Referring to the drawings:

Fig. 1 is a front elevation of a portion of a 105 linotype machine equipped with the improved device;

Fig. 2 is a vertical section taken through the vise frame, and showing the device as viewed from the left, some of the parts being broken 110

away to reveal the interior construction and arrangement;

Fig. 3 is a front elevation of a portion of the device, showing the large cam in operative position, certain parts being broken away to show the construction of the cam shifting mechanism;

Fig. 4 is a view similar to Fig. 3, showing the small cam in operative position;

Fig. 5 is a perspective view, showing the construction of the left-hand jaw and the cam adjusting connections associated therewith;

Fig. 6 is an enlarged perspective view of the cam shifting mechanism;

Fig. 7 is a front elevation, showing the right-hand jaw as moved back to permit a two em expansion of the line during justification when that jaw is used for quadding;

Fig. 8 is a view similar to Fig. 7, showing the right and left-hand jaws moved back one em each to permit a two em expansion of the line during justification when both jaws are used for centering; and

Figs. 9 and 10 are elevations of the large cam in different initial set positions (full lines) and different final positions (dotted lines) under different conditions.

The matrices X and the expandable spacebands Y (see Figs. 7 and 8) are composed in line in the assembler A under the restraining influence of a line resistant (not shown) which can be set for lines of different length, all in the usual way. After the line has been composed, the assembler is raised to position the line between the fingers of the line delivery carriage B, which thereupon moves to the left (and in doing so inaugurates the operation of the machine) and transfers the composed line through the intermediate channel B¹ into the vertically movable transporter or first elevator C slidably mounted in the vise frame D. Upon receiving the line, the first elevator immediately descends to position it between the left-hand jaw E and the right-hand jaw F and in front of the slotted mold G, which latter then advances from the rear and into contact with the line and the two clamping jaws for the slug casting operation, the line, prior to casting, being aligned and justified in the usual way when the machine is being operated under the usual conditions. After the slug has been cast, the mold is carried from its horizontal casting position (as shown in Fig. 1), to a vertical ejecting position by a three-quarter rotation of the mold disc G¹, the first elevator in the meantime being raised to deliver the composed line to the matrix and spaceband distributing devices and finally coming to rest in its original or line receiving position, as shown in Fig. 1.

As already stated, the invention disclosed in the co-pending application Serial No. 658,077 provides a device whereby the line clamping jaws may be operated automatically to cooperate with lines of less than full length so as to cast slugs with blank spaces at either end, as for "quadding", or at both ends, as for "centering". It should be stated perhaps that each of the jaws E and F is made long enough, when used alone for quadding, to close that part of the mold slot left exposed by a short composed line, or in the absence of a composed line, to close the mold slot completely. Except as thus modified, and as hereinafter noted, the two jaws are substantially the same as those employed in the commercial machines and they are mounted for movement in the vise frame D in the customary manner, being carried by supporting blocks E¹

and F¹ slidable in suitable guideways formed in the vise frame D.

The two jaws E and F are movable toward and from each other by a periodically operated part in the form of a vertically movable rod H which may be connected at its upper end to the respective jaws through the medium of two similar but oppositely disposed bell-crank levers E² and F² pivoted at E³ and F³ to the vise frame D, the longer arms of said levers being connected by short links E⁴ and F⁴ to the jaw supports E¹ and F¹, respectively, and the shorter arms of said levers being arranged for connection to the rod H. According to this arrangement, when the rod H is moved downwardly from its uppermost position (which is its normal position of rest, as shown in Fig. 1), it will move the two jaws equidistantly toward each other (assuming both to be connected to the rod) until they contact with the opposite ends of a composed line which has previously been positioned between them, and when the rod is moved upwardly for restoration to its position of rest, it will in like manner move the jaws equidistantly away from each other to return them to their original positions of maximum separation. Since the composed lines positioned between the jaws may vary in length, the actual extent of movement of the rod H will of course vary accordingly, and hence provision is made for such varied movement of the rod in its actuating connections as will presently appear.

In providing for connection and disconnection of the rod H with and from the jaws E and F, the rod carries at its upper end a grooved collar N¹ mounted for rotation only and segmentally formed for engagement with diametrically opposed pins N⁴ (only one being shown, see Fig. 1), protruding inwardly from the extremities of the horizontal arms of the actuating levers E² and F² for the jaws E and F, respectively. When both jaws are to be connected to the rod H for centering, the collar is turned to the position which brings both of its segments into engagement with the pins N⁴ of the jaw actuating levers E² and F². When both jaws are to be disconnected from the rod H for regular machine operation, the collar is turned to locate the segments out of engagement with the pins N⁴. In connecting the rod H to either of the jaws independently, the collar is moved to intermediate positions, the appropriate segment being brought into engagement with the desired pin N⁴, say the pin N⁴ shown in Fig. 1 of the lever E² when selecting the left-hand jaw.

While the collar N¹ could be turned directly by hand, a special control device is employed for setting the collar instantly in the required position. This device is shown in the form of a manually operable bar O mounted to slide in a horizontal guide O¹ of the vise frame D and disposed at right angles to the rod H. Suitable connections are provided between the bar O and the rotatable collar N¹, and a detailed description thereof may be found in co-pending application Serial No. 658,077 above referred to.

The setting of the bar O is effected by means of a horizontally disposed hand lever O², pivoted at its rear end at O³ to a bracket extending rearwardly from the guide O¹ on the vise frame and loosely pivoted about midway of its length, as at O⁴, to the bar O (see Fig. 6). As a guide to the operator, the bar O is provided with a pointer O¹⁰ which cooperates with a scale on the vise frame bearing the designations "REG", meaning regular machine operation, "R", meaning right jaw quadding, "C", meaning centering, and "L", meaning left jaw quadding.

J in the downwardly moved or line clamping position of the rod.

Referring particularly to Figs. 2 and 3, it will be noted that at its lower end the rod H is provided with a fixed collar T¹ which contains an expansion spring T² encircling the rod H and pressing upwardly on the lower end of the sleeve T. This lifting tendency of the spring T², however, in the downwardly moved position of the rod H, is resisted and overcome by a rotary cam (in the present instance either of two cams V or V¹¹ which may be at the time in operative position) rotatably mounted on the sleeve at its upper end and arranged in position to engage a roller h arranged on the collar H¹ fixed to the rod. When the cam in operative position is set with its high point in contact with the roller h, it will by reacting thereagainst and over the opposition of the spring T², hold the sleeve T in contact with the second collar T¹ at the lower end of the rod. Under such a setting of the cam, as will now be evident, there can be no relative movement between the rod and the sleeve, and the two parts function as if they were rigidly united, which is the condition that should exist when casting from lines without spacebands. On the other hand, when the cam is set, say to bring its lowest point into contact with the roller h, then the sleeve T in the downwardly moved position of the rod H will be raised by the spring T² out of engagement with the collar T¹, and the clearance thus provided will determine the amount of relative movement which can take place between the rod and sleeve after the locking of the latter by the toggle member J in the manner before described. This is a condition which should exist when it is desired to permit of the maximum spread of a composed line during justification, which ordinarily is three ems. When it is desired to provide for a less spread of a composed line, the cam is set in an intermediate position, that is to say in a position intermediate its lowest and highest points.

The upward movement of the rod H to spread jaws for expansion of the line is effected by mechanism not herein shown (but fully shown and described in the co-pending application), this mechanism being operated by a cam arranged on the main drive shaft of the machine and acting through the lever H¹⁰ which actuates the rod H. The cam just referred to comes into operation after the sleeve T has been locked in its downward position by the toggle member J and acts against the opposition of the spring H¹⁴ to rock the lever H¹⁰ and move the rod H upwardly with reference to the sleeve T until the rod collar T¹ banks against the lower end of the sleeve, the extent of such relative movement of the rod being, as previously stated, determined by the setting of the cam which is in operative position. It is this upward limited movement of the rod H which moves the line clamping jaws outwardly from their line contacting position and thus determines the final quadding or centering position of the jaws when a composed line is to be spread or justified by the expansion of the contained spacebands. The arrangement is such that the cam on the main drive shaft of the machine which effects the spreading of the jaws for justification is rotated beyond its operative position prior to casting and, hence, if for any reason the line has not been fully expanded during justification, the spring H¹⁴ will operate to pull the rod H downwardly until the jaws are moved into contact with the line, and through safety

means not forming a part of the present invention (but shown and described in the co-pending application), this downward movement of the rod H operates to prevent the machine from casting.

In the commercial machines, the slug casting operation is controlled by a pivoted lever L (see Fig. 1) mounted on the machine frame and which actuates a pump stop. The pump stop normally stands in position to prevent casting, and the lever must be moved to the right, as viewed in Fig. 1, in order to release the pump. Ordinarily, this pump releasing movement of the lever L is effected during the justification of the line by a slight yielding to the right of the right-hand jaw F which engages directly with the lever, but since this jaw when used for quadding or centering must be moved away from instead of toward the lever, means are provided for operating the lever by the leftward movement of the jaw to quadding or centering position, such movement of the jaw being transmitted through the composed line to a train of connections leading to the pump stop lever.

The connections referred to are not shown herein (being fully disclosed in the co-pending application), but are operated through a vertically arranged pivoted section L¹ carried by the left-hand jaw E and projecting inwardly beyond the matrix engaging face of the jaw, the section L¹ being provided with a projection L² which, during movement of the section toward the left (see Fig. 5), effects a camming action on a parallel motion bar (not shown), the motion of which is transmitted through the remaining connections to operate the pump stop lever L. Hence, in the event that the line is not tightly clamped between the jaws E and F, the section L¹ will not be moved to release the pump stop and the machine will fail to cast.

Another contingency must also be cared for: When the jaws are to be spread to allow a certain predetermined expansion of the line, and the spacebands contained therein are insufficient to effect the proper spread, the jaws after being moved outwardly to allow for the expansion, will, after justification, move inwardly into contact with the line, and a line of less than the desired length will be cast. To prevent this, a parallel motion bar R (Fig. 1) is mounted on the sleeve T by a pair of pivoted connecting links R¹ and R² and cooperates with an upright lever R⁴ which controls the operation of the pump stop lever L in the required manner, all as fully set forth in the Frolander application.

The parts and their operation as thus far described are the same as those found in the commercial machines or the patent to O. Mergenthaler No. 436,532, and the Frolander application, Serial No. 658,077, repeatedly referred to, and while some of the parts and their operation have been described herein as an introduction to the present invention, a more complete description may be had by reference to said application.

As already stated, in the Frolander application, a single cam, adapted to be adjusted manually in changing from one measure to another, is provided to determine the maximum extent of line spread during justification for a given measure, and this one cam is utilized whether only one jaw is to be used, as when quadding, or both jaws are used, as when centering. Of course, with this arrangement it is necessary when centering that the adjustment of the cam be just half of that required when quadding, since both jaws are

meaning left jaw quadding. These designations indicate the four positions of the hand lever, and suitable means, such as a detent, may be employed to maintain the lever in any of the four set positions. On its underside, the hand lever O^7 is formed with a raised boss or cam O^{20} , which forms a part of the present invention and will be further described in connection therewith at a later point.

- 10 In the operation of the machine, when the rod H occupies its uppermost or normal position of rest, the connection between its collar N^1 and the bar O is established so that, by manipulation of the hand lever O^7 , the machine may be conditioned for quadding, centering or regular operation. However, during the operation of the machine, when the bar H is moved downwardly, this connection is broken, and in order to maintain the setting of the parts, locking means are provided, all as fully set forth in the aforesaid co-pending application.

The rod H is slidable in suitable bearings H^2 and H^3 of the fixed vise frame D , being provided about midway of its length with a collar H^1 carrying an adjusting screw (not shown) which banks against the underside of the bearing H^2 when the rod is in its uppermost or normal position of rest. At its lower end, the rod H is connected by a link H^9 to the forward end of a lever H^{10} , having a hub portion H^{11} journalled on a pivot rod H^{12} carried by a bracket (not shown) secured to the vise frame D (see Fig. 1). Fixed to and depending from the hub portion H^{11} is a barrel or cylinder H^{13} containing an expansion spring H^{14} pressing upwardly against a lug (not shown) projecting forwardly from a hub portion H^{16} of a second lever H^{17} also journalled on the pivot rod H^{12} . The lifting tendency of the spring H^{14} is resisted and overcome by the engagement of a stop lug on the hub portion H^{16} on the second lever H^{17} with a stop lug formed on the hub portion H^{11} of the first lever H^{10} , the effect of this arrangement being to cause the two levers to move in unison until the first lever H^{10} is arrested by a downward movement of the rod carrying sleeve H^1 .

The operating connections for the lever H^{17} are not shown herein, being dealt with in detail in the co-pending application Serial No. 658,077. For present purposes, it will suffice to say that a cam is provided on the main drive shaft of the machine, and the rotation of this cam (which is always in a clockwise direction and which makes one complete rotation at each cycle of operation of the machine) is imparted to the rod H through a train of connections leading from the cam to the lever H^{17} and from there on through the train of connections previously described whereby the rod H is first moved downwardly to effect the inward or closing movement of the jaws E and F , and then upwardly to effect the outward or separating movement of the jaws. Since the downward movement of the rod H will vary according to the length of the composed line positioned between the jaws, its actuating connections must be arranged to yield as the rotation of the cam on the main drive shaft continues, and this yielding is provided by the lost motion which takes place between the two levers H^{10} and H^{17} , the latter acting on the former through the expansion spring H^{14} which, of course, will be compressed to absorb the lost motion. By the use of this lost motion arrangement, the lever H^{17} may be operated positively by the cam on the main drive shaft and permitted to partake of

a full rocking movement regardless of the extent of movement of the rod H .

In order to lock the rod H in its downwardly moved position, there is provided a toggle member J (see Fig. 2) enclosed within a box or housing D^1 which carries the bearing H^3 before alluded to. This toggle member J operates a clamp or grip element J^1 arranged to contact with a sleeve T carried by the rod H and which, for purposes of the present description, may be assumed to be integral with the rod. Associated with the toggle is an actuating link J^2 provided at its upper end with an adjusting screw J^3 arranged to bear upon the toggle joint. At its lower end, the link J^2 is connected by a turn-buckle link J^4 to the forward laterally bent arm J^5 of the lever H^{17} before referred to. As will be noted in Fig. 2, the link J^2 is slotted as at J^6 so as to straddle the toggle joint, being encircled within the box D^1 by a small compression spring (not shown) which normally presses upwardly on the toggle joint to maintain the grip element J^1 in inactive position.

It will now be seen that the toggle member J is operated by reason of the lost motion which takes place between the two levers H^{10} and H^{17} , it being remembered that the former lever is the one connected to the rod H . In other words, after the lever H^{10} is arrested in its movement by the downward movement of the rod H (due of course to the contact of the jaws with the opposite ends of a composed line), the lever H^{17} continues to move to its full extent under the influence of the actuating cam on the main drive shaft of the machine, acting in the meantime to continue its drawing down of the link J^2 . The length of the link J^2 (or what amounts to the same thing, the position of the screw J^3 thereon) is such that, during the last portion of the movement of the lever H^{17} , the screw J^3 is moved down within the box D^1 and caused to actuate the toggle member J so as thereby to press the grip element J^1 under heavy pressure against the sleeve T and lock the rod H securely in its downwardly moved position. It may be explained in passing that the toggle member J is so designed that its members will never pass dead center. Later, after the slug has been cast and it becomes necessary to restore the jaws to their original positions, the link J^2 is raised in advance, so as to unlock the rod H and its sleeve T to permit the raising of the rod, the link during the raising of the rod passing through the box or housing D^1 and the aforementioned spring acting instantly to withdraw the grip element J^1 from engagement with the sleeve T .

Were the rod H and its sleeve T actually joined together as one (as above assumed), it is plain that there could be no spread of the composed lines after the sleeve is locked in position by the toggle member J , and in such circumstances, the jaws would be locked directly in their line contacting positions, which actually happens when the lines are composed without spacebands. However, the arrangement is such that the jaws may be moved outwardly from their line contacting positions, to a limited extent, after the locking of the sleeve T in order that a composed line may be spread to a corresponding extent under the expanding influence of the spacebands Y , provision being made for allowing the line to spread up to three ems in extent. This is accomplished, as before stated, by provision of a relative movement between the rod H and the sleeve T after the latter has been locked by the toggle member J .

moved outwardly instead of only one, and the movement of the rod H is transmitted equally to both jaws. Thus, the same movement of the rod H relative to the sleeve T, which would allow for say a one em spread if but one jaw were connected to it, will allow for a two em spread when both jaws are connected.

In accordance with the present invention, it is proposed to utilize the two cams V and V¹¹, before alluded to, for controlling the amount of relative movement between the sleeve T and the rod H to determine the extent of outward movement of the jaws during justification. The cams V and V¹¹ are mounted on a common axis but differ in eccentricity, and the larger cam V is utilized when centering while the smaller cam V¹¹, which has the greater eccentricity, is used when quadding.

Preferably, the cams V and V¹¹ are formed integrally on a bushing member V¹², which is slidably axially on a sleeve V¹³ supported by a pin V¹ projecting from the upper sleeve band T³. Also formed on the member V¹² are circular flanges or collars V¹⁴ and V¹⁵ spaced apart to form a yoke by means of which the member may be shifted axially on the sleeve V¹³ to bring one or the other of the cams into operative position relative to the roller h (before mentioned) carried by a pin h¹ projecting from the collar H¹. A spring detent V¹⁶, arranged on the flange V¹⁵ and adapted to seat in one or the other of a pair of grooves V¹⁷ formed in the sleeve V¹³, serves to maintain the member V¹² in its shifted position.

A forwardly extending arm V³ (see Figs. 2 and 6), formed with an elongated slot V⁴, is secured to the outer end of the sleeve V¹³ and provided with a pin V¹⁸ projecting into an aperture formed in the flange V¹⁵ for the purpose of rotating the member V¹² on the sleeve V¹³. The pin V¹⁸ fits loosely within the aperture, so that the member V¹² may be shifted freely, and is made long enough to maintain its engagement with the flange V¹⁵ in either shifted position of the member V¹². The slot V⁴ in the arm V³ receives a pin V⁵ projecting from the end of a second arm V⁶ pivotally mounted on a bolt V¹⁹ fastened to the vise frame D. About midway of its length, the arm V⁶ is pivotally attached to the lower end of a rod V²⁰, which latter is formed in two sections held together by a knurled turnbuckle V²¹ provided to lengthen or shorten the rod V²⁰ and thereby effect initial working adjustment of the cams V and V¹¹. The upper portion of the rod V²⁰ is slidably in a bearing formed in the vise frame D, and is provided at a point below the bearing with a collar V²², between which collar and the vise frame a coil spring V²³ is arranged. At its upper extremity, the rod V²⁰ is pivotally attached to one arm V²⁴ of a fore-and-aft lever V²⁵ pivotally mounted as at V²⁶ to a bracket V²⁷ secured to the vise frame D (Fig. 2). The other arm V²⁸ of the lever V²⁵ is arranged to play in a horizontal slot V²⁹ formed in a right angularly disposed plate V³⁰, which is supported by a pair of parallel motion links V³¹ on the jaw support E¹. The front face of the left-hand jaw E is formed with a longitudinal recess to receive the plate V³⁰, and the upper wall E⁵ of the recess is bevelled or inclined downwardly toward the left, the upper edge of the member V³⁰ being correspondingly formed.

With this arrangement, when the left-hand jaw E occupies its fully retracted position or is set for a line of full measure, the spring V²³ urges the rod V²⁰ all the way down and, through the arms V⁶ and V³, maintains the cam V or

V¹¹ (whichever is in operative position) with its highest point in engaging relation to the roller h and thus holds the rod H and sleeve T against relative movement in the downwardly moved position of the rod. On the other hand, when the left-hand jaw E is adjusted inwardly to any desired set position for a line of less than full measure, the inclined surface E⁵ cams the plate V³⁰ downwardly and with it the arm V²⁸ of the lever V²⁵, causing the latter to be rocked about its pivot V²⁶, and raising the rod V²⁰ against the action of the spring V²³ to rotate the member V¹² and change the adjustment of the cam V or V¹¹ in accordance with the setting of the jaw. In short, the adjustment of the left-hand jaw E for a line of any given measure automatically effects a corresponding adjustment of the operative cam V or V¹¹ to determine the amount of relative movement between the rod H and the sleeve T or the full extent of the outward or line spread movement of the jaw or jaws during justification of that given length line.

It will be recalled that the rod H is connected by the lever E² to the slidable left-hand jaw-supporting block E¹, so that when the jaw E is moved from its particular set position into line contacting position, it is carried by the supporting block E¹, there being no relative movement between them. When the supporting block E¹ is thus moved, it also carries with it the plate V³⁰, but since the slot V²⁹ is horizontally disposed, the relative movement between the plate V³⁰ and the lever V²⁴ will in no way affect the latter or alter the initial setting of the cam in use.

The mechanism employed for shifting the cam member V¹² comprises a rod P (see Figs. 3, 4 and 6) slidably mounted in bearings P¹ and P², formed in brackets P³ and P⁴, respectively, secured to the vise frame D. The rod P is provided with a pin P⁵ which projects through a slot P⁶ formed in the lower side of the bearing P¹ and is arranged to enter between the flanges V¹⁴ and V¹⁵ on the member V¹² when the rod H occupies its uppermost position. The slot P⁶ runs parallel with the member V¹² so that movement of the rod P from left to right or vice versa, as viewed in the drawings, will effect a corresponding movement of the member V¹² on the sleeve V¹³. Adjacent the bearing P², the rod P is formed with an enlarged portion P⁷ having a flat face P⁸ on which there is located a roller P⁹ mounted on a pin P¹⁰. The roller P⁹ is adapted to engage in a diagonally disposed groove or channel P¹¹ formed in a block P¹² secured, as by a screw P¹³, to the lower end of a plunger P¹⁴, which latter is arranged in a fixed vertically disposed bearing or sleeve P¹⁵ formed in the bracket P². The upper end of the plunger P¹⁴ projects beyond the top edge of the bearing P¹⁵, as at P¹⁶, and is normally held in its uppermost position by a tension spring P¹⁷ which is connected at one end by a pin P¹⁸ to the lower end of the plunger P¹⁴ and at its other end by a conveniently located thumb-screw P¹⁹ to the fixed bearing P¹⁵. Pivotally mounted at P²⁰ to an extended portion P²¹ of the bracket P² is a lever P²², the free end P²³ of which engages with upper end of the plunger P¹⁴. On its upper edge, the lever P²² is formed with a pair of raised bosses P²⁴ and P²⁵, between which there is arranged a roller P²⁶ mounted on a pin P²⁷, the roller being adapted to be engaged by the previously mentioned boss O²⁰ on the control lever O⁷ when the latter is moved into position to condition the machine for centering.

The thumb-screw P^{19} is formed with a tapered tip adapted to engage in a small recess or depression P^{28} formed in the plunger P^{14} . If at any time when the machine is to be conditioned 5 for quadding rather than centering and a reduced line spread is desired, the thumb-screw P^{19} may be set up into engagement with the recess P^{28} . Thereafter, when the lever O^7 is moved to the 10 right or left to condition the machine for quadding, carrying the boss O^{20} out of engagement with the roller P^{26} on the lever P^{22} , the plunger nevertheless will be held in its depressed condition as shown in Fig. 6 and the large cam V will be maintained in operative position to act 15 upon the roller h and control the spread of the line.

Under ordinary circumstances, however, the thumb-screw P^{19} is locked out of engagement with the recess P^{28} by a lock-nut P^{29} , so that when 20 the control lever O^7 is set for either right or left-hand quadding, the spring P^{17} exerts itself to maintain the plunger P^{14} in its upper position, in which condition of the parts (see Fig. 4) the small cam V^{11} is in operative position 25 to act upon the roller h and control the line spread. When the lever O^7 is moved to the position shown in Fig. 6, for centering, the boss O^{20} engages the roller P^{26} and effects a camming action thereon to rock the lever P^{22} about its pivot P^{20} and depress the plunger P^{14} against the tension of the spring P^{17} . As the plunger P^{14} moves downwardly, carrying with it the block P^{12} , the roller P^{10} , tracking in the channel P^{11} , is cammed to the right and shifts the rod P in 30 that direction to bring the large cam V into action (see Fig. 3).

In the embodiment illustrated, it is also proposed to rotate the cam V or V^{11} automatically as the rod H is moved downwardly to bring the 40 clamping jaws into contact with the composed line, as in the Frolander application, and it is for this reason that the rod V^{20} , instead of being connected directly to the cam member V^{12} , is secured to the lever V^6 which is connected to the 45 cam member through the lever V^3 . When the member V^{12} is carried downwardly with the rod H , the lever V^3 , due to its pin and slot connection with the lever V^6 (which latter, of course, is held against movement), will also move downwardly and at the same time rock about the pin V^5 , turning the member V^{12} (and therefore the cams V and V^{11} mounted thereon) clockwise (as viewed in Fig. 6) or in a direction to bring 50 higher portions of the active cam into contact with the roller h and thereby reduce the space between the rod collar T^1 and the lower end of the sleeve T .

The extent of turning of the cam member V^{12} will, of course, depend upon the extent of the 60 downward movement of the sleeve T . Thus, if the sleeve should be carried to its lowermost position, as when there is no line between the clamping jaws, the member V^{12} will be turned to bring the highest portion of the active cam into 65 contact with the roller h and in such case no clearance space will remain between the sleeve and the collar T^1 . On the other hand, if the sleeve should be carried only part way down, as when there is a line between the clamping jaws, the turning of the member V^{12} will be less but 70 will vary according to the length of the line, being greater for shorter lines and lesser for longer lines.

In Figs. 9 and 10, there is diagrammatically 75 illustrated the effect of the automatic initial set-

ting of the active cam (which happens to be the cam V) by the adjustment of the left-hand jaw into set position, and also the automatic change in the adjustment of the cam which comes from the downward movement of the rod H and sleeve T in moving the jaw or jaws into line contacting position. Referring first to Fig. 9, the cam and its associated parts are shown by the full lines in their normal position of rest when the left-hand jaw occupies its full line position. By the dotted lines, there is indicated the manner in which the roller h first comes into contact with the cam as the rod and sleeve begin their downward movement, and then the cam rotated to bring a higher point into engagement with the roller h as the rod and sleeve continue their downward movement, it being understood that such rotation of the cam is brought about by the rocking and sliding movement of the lever V^3 about the relatively fixed pin V^5 . The showing in Fig. 10 is substantially the same as that of Fig. 9, except that by the full lines the cam V is shown as initially presenting a higher point for engagement with the roller H^3 due to the manual adjustment of the left-hand jaw into a desired set position for a line of less than full length, whereby initially the spread of the line is reduced to correspond, and by the dotted lines there is shown the rotation of the cam due to the downward movement of the rod and sleeve, whereby a still further reduction of the line spread will be effected. Comparing Figs. 9 and 10, it will be noted that the latter shows a greater rotation of the cam than the former. This is the result when a short line is presented to the 100 mold and the rod and sleeve partake of a greater downward movement in bringing the jaw or jaws into contact with the line. In this connection, it may be stated that the operation is the same regardless of which cam is in use, although naturally the extent of movement will be different in the two cases. Thus, as will be clear from Figs. 7 and 8, when the small cam V^{11} is used for quadding (Fig. 7), the line spread movement of the rod H , being confined to one jaw only, 105 will be twice as great for a given line spread as when the large cam V is used for centering (Fig. 8), at which time the rod H is connected to both jaws.

In the accompanying drawings, the invention 110 has been shown in preferred form and by way of example, and as applied to the machine of the class stated, but obviously many modifications and alterations may be made therein and in its mode of operation without departing from the spirit of the invention. It should, therefore, be understood that the invention is not limited to any specific form or embodiment, except insofar as such limitations are specified in the appended claims.

Having thus described our invention, what we claim is as follows:

1. In a slug casting machine, the combination of a pair of line clamping jaws, one of said jaws being adjustable toward the other to accommodate lines of different lengths, means for moving one of the jaws inwardly from its line receiving position into contact with a composed line, said jaw being thereafter movable outwardly a limited distance from its line contacting position, and means controlled by the set position of the adjustable jaw for determining the extent of such outward movement for lines of a given length.
2. In a slug casting machine, the combination 150

- of a pair of line clamping jaws, one of said jaws being adjustable toward the other to accommodate lines of different lengths, means for moving one of the jaws inwardly from its line receiving position into contact with a composed line, said jaw being thereafter movable outwardly a limited distance from its line contacting position, and automatic means controlled by the adjustment of said adjustable jaw for determining the extent of such outward movement for lines of a given length. 5
3. A combination as set forth in claim 1, including further means operable automatically by the inward movement of the movable jaw from its line receiving position into contact with the line to vary the extent of its outward movement for lines of less than the given length. 10
4. A combination as set forth in claim 1, including automatic means for progressively reducing the extent of the outward movement of the movable jaw from its line contacting position in proportion to the extent of its inward or line contacting movement. 15
5. In a slug casting machine, the combination of a pair of line clamping jaws, one of said jaws being adjustable toward the other to accommodate lines of different lengths, means for moving one of the jaws inwardly from its line receiving position into contact with a composed line, means for thereafter moving said jaw for a limited distance outwardly from its line contacting position to permit justification of the line, and means controlled by the adjustment of the adjustable jaw as well as by the inward movement of the movable jaw for respectively determining and varying the extent of the outward movement of the movable jaw from its line contacting position. 20
6. In a slug casting machine, the combination of a pair of line clamping jaws, one of said jaws being adjustable to different set positions for lines of different lengths and being movable from its set position into line contacting position, means for thereafter moving said jaw for a limited distance outwardly from its line contacting position, and means controlled by the adjustment of the jaw into its set position as well as by its movement into line contacting position for respectively determining and varying the extent 25 of the outward movement of the jaw from its line contacting position. 40
7. In a slug casting machine, the combination with a left-hand line clamping jaw and an opposed right-hand line clamping jaw, the left-hand jaw being adjustable toward the right-hand jaw to different set positions to accommodate lines of different lengths, of means for moving the left-hand jaw from its set position into contact with a composed line, said jaw being thereafter movable outwardly a limited distance from its line contacting position, and means controlled by the set position of the left-hand jaw for determining the extent of its outward movement. 50
8. In a slug casting machine, the combination with a left-hand line clamping jaw and an opposed right-hand line clamping jaw, the left-hand jaw being adjustable toward the right-hand jaw to different set positions to accommodate lines of different lengths, of means for moving the left-hand jaw from its set position into contact with a composed line, said jaw being thereafter movable outwardly a limited distance from its line contacting position, means controlled by the set position of the left-hand jaw for determining the extent of its outward movement, and further means controlled by the extent of inward movement of the right-hand jaw into line contacting position to vary the extent of its outward movement from that position. 55
9. In a slug casting machine, the combination with a left-hand line clamping jaw and an opposed right-hand line clamping jaw, the left-hand jaw being adjustable toward the right-hand jaw to different set positions to accommodate lines of different lengths, of means for moving one of the jaws inwardly from its line receiving position into contact with a composed line, said jaw being thereafter movable outwardly a limited distance from its line contacting position, and automatic means controlled by the adjustment of the left-hand jaw for determining the extent of such outward movement for lines of a given length. 60
10. In a slug casting machine, the combination with a left-hand line clamping jaw and an opposed right-hand line clamping jaw, the left-hand jaw being adjustable toward the right-hand jaw to different set positions to accommodate lines of different lengths, of means for moving one of the jaws from its line receiving position into contact with a composed line, said jaw being thereafter movable outwardly a limited distance from its line contacting position, automatic means controlled by the adjustment of the left-hand jaw for determining the extent of such outward movement for lines of a given length. 65
11. In a slug casting machine, the combination with a left-hand line clamping jaw and an opposed right-hand line clamping jaw, the left-hand jaw being adjustable toward the right-hand jaw to different set positions to accommodate lines of different lengths, means for moving the right-hand jaw inwardly from its line receiving position into contact with a composed line, said right-hand jaw thereafter being movable outwardly for a limited distance from its line contacting position, and means controlled by the set position of the left-hand jaw for determining the extent of such outward movement of the right-hand jaw. 70
12. In a slug casting machine, the combination with a left-hand line clamping jaw and an opposed right-hand line clamping jaw, the left-hand jaw being adjustable toward the right-hand jaw to different set positions to accommodate lines of different lengths, means for moving the right-hand jaw inwardly from its line receiving position into contact with a composed line, said right-hand jaw thereafter being movable outwardly for a limited distance from its line contacting position, means controlled by the set position of the left-hand jaw for determining the extent of such outward movement of the right-hand jaw, and further means controlled by the extent of the inward movement of the right-hand jaw into line contacting position to vary the extent of its outward movement from that position. 75
13. In a slug casting machine, the combination with a left-hand line clamping jaw and an opposed right-hand line clamping jaw, the left-hand jaw being adjustable toward the right-hand jaw to different set positions to accommodate lines of different lengths, means for moving both jaws inwardly from their line receiving position into contact with a composed line, said jaws there- 80

- after being movable outwardly for a limited distance from their line receiving position, and means controlled by the set position of the left-hand jaw for determining the extent of such outward movement of the two jaws. 80
14. In a slug casting machine, the combination with a left-hand line clamping jaw and an opposed right-hand line clamping jaw, the left-hand jaw being adjustable toward the right-hand jaw to different set positions to accommodate lines of different lengths, means for moving both jaws inwardly from their line receiving position into contact with a composed line, said jaws thereafter being movable outwardly for a limited distance from their line receiving position, means controlled by the set position of the left-hand jaw for determining the extent of such outward movement of the two jaws, and further means controlled by the extent of the inward movement of the two jaws into line contacting position to vary the extent of their outward movement from that position. 85
15. A combination according to claim 1, wherein in the inward movement of the movable jaw or jaws is a quadding or centering movement and wherein the outward movement of said movable jaw or jaws is from quadding or centering position. 90
16. In a slug casting machine, the combination of a pair of line clamping jaws, one of said jaws being adjustable toward the other to different set positions to accommodate lines of different measure, means for moving one jaw inwardly into contact with a composed line, means for thereafter moving said jaw outwardly for a limited distance from its line contacting position, an adjustable cam cooperating with the latter means to determine the extent of such outward movement, and operative connections between the adjustable cam and the adjustable jaw, whereby the latter determines the extent of the outward movement of the movable jaw. 95
17. A combination as set forth in claim 16, including means controlled by the inward movement of the movable jaw into line contacting position for effecting a further adjustment of the cam to reduce the extent of the outward movement of said jaw as the length of the composed line decreases from a given measure to a smaller measure. 100
18. In a slug casting machine, the combination of a pair of line clamping jaws, means for moving one of said jaws inwardly toward the other for quadding or for moving both jaws toward each other for centering, means for thereafter moving said jaws outwardly for a limited distance from line contacting position, and means for determining the extent of such outward movement of the jaws, said means including a pair of cams, one for centering and the other for quadding, movable into operative position as required. 105
19. In a slug casting machine, the combination of a pair of line clamping jaws, means for moving one of said jaws inwardly toward the other for quadding or for moving both jaws toward each other for centering, means for thereafter moving said jaws outwardly for a limited distance from line contacting position, means operable to condition the machine for quadding or for centering, and means for determining the extent of such outward movement of the jaws, said means including a pair of cams, one for centering and the other for quadding, and connections from the machine conditioning means for automatically selecting one cam or the other for use. 110
20. In a slug casting machine, the combination of a pair of line clamping jaws, means for moving one of said jaws inwardly toward the other for quadding or centering, means for thereafter moving said jaw outwardly for a limited distance, means for determining the extent of such outward movement of the jaw when quadding, and other means for determining the extent of such outward movement of the jaw when centering. 115
21. A combination according to claim 20, including means for automatically selecting one determining means or the other according as the machine is conditioned for quadding or centering. 120
22. A combination as in claim 19, wherein the machine conditioning means includes a hand lever movable to different positions for quadding or centering, and wherein the cam selecting connections include means operated by said hand lever for shifting the cams to bring one or the other into operative position. 125
23. A combination as in claim 19, wherein, the machine conditioning means includes a hand lever movable to different positions for quadding or centering, and wherein the cam selecting connections include means operated by said hand lever for shifting the cams to bring one or the other into operative position, characterized by the fact that the cams are mounted on a shiftable bushing by which one or the other is brought into operative position, and that the shifting of the bushing is effected by a roller arranged on a shifting member associated with the bushing and engaging a cam surface carried by a plunger controlled in its actuation by the hand lever which conditions the machine for quadding or centering. 130
24. In a slug casting machine equipped with left-hand and right-hand line clamping jaws, a quadding and centering device, and means to spread the jaws to permit expansion of the line during justification, the combination of means controlled by the setting of the left-hand jaw for determining the extent of spread of the jaws, said means including a rotatable cam operative to control the jaw spreading means, a vertically movable member arranged in a recess formed in the left-hand jaw and having an inclined surface bearing against a correspondingly inclined surface presented by said recess, the member being supported by two parallel motion links to permit it to move vertically as the jaw is adjusted relatively thereto to different set positions, and connections between said member and rotatable cam whereby the vertical movement of the member will effect the rotation of the cam. 135
25. A combination as in claim 24, wherein the member associated with the jaw is formed with a horizontal longitudinal slot to permit a free relative movement between it and its connections with the cam, whereby the member may move with the jaw without affecting the cam. 140
26. In a slug casting machine equipped with left-hand and right-hand line clamping jaws, a quadding and centering device, and means to spread the jaws to permit expansion of the line during justification, the combination of a pair of rotary cams for controlling the extent of spread of the jaws, and means for bringing one or the other of the cams into operative position according as the machine is conditioned for quadding or centering. 145
27. In a slug casting machine, the combination of a pair of line clamping jaws, a vertically 150

- movable rod connected to at least one of said jaws, means for moving the rod downwardly to effect a closing movement of the jaws and then upwardly to effect a separating movement of the jaws, means for locking the rod in its downwardly moved position with capacity for a limited upward movement to permit of a corresponding separation of the jaws during justification, means independent of the line for effecting such limited upward movement of the rod, a pair of cams movable with the rod and adjustable with reference thereto to control the extent of its upward movement after locking, means for rendering one of said cams active and the other inactive as required, and means for adjusting the active cam in varying the upward movement of the rod, said means being controlled by the setting of the jaws for lines of a given measure and also by the closing of the jaws during quadding or centering for contact with lines of less than said given measure. 80
- 5 28. In a slug casting machine, the combination of a pair of line clamping jaws, a vertically movable rod connected to at least one of said jaws, means for moving the rod downwardly to effect a closing movement of the jaws and then upwardly to effect a separating movement of the jaws, means for locking the rod in its downwardly moved position with capacity for a limited upward movement to permit of a corresponding separation of the jaws during justification, means independent of the line for effecting such limited upward movement of the rod, a pair of cams movable with the rod and adjustable with reference thereto to control the extent of its upward movement after locking, means for rendering one of said cams active and the other inactive as required, and means for adjusting the active cam in varying the upward movement of the rod. 90
- 10 29. In a slug casting machine, the combination of a pair of line clamping jaws, a vertically movable rod connected to at least one of said jaws, means for moving the rod downwardly to effect a closing movement of the jaws and then upwardly to effect a separating movement of the jaws, means for locking the rod in its downwardly moved position with capacity for a limited upward movement to permit of a corresponding separation of the jaws during justification, means independent of the line for effecting such limited upward movement of the rod, a pair of cams movable with the rod and adjustable with reference thereto to control the extent of its upward movement after locking, means for rendering one of said cams active and the other inactive as required, and means for adjusting the active cam in varying the upward movement of the rod. 95
- 15 30. In a slug casting machine, the combination of a pair of line clamping jaws, a vertically movable rod connected to at least one of said jaws, means for moving the rod downwardly to effect a closing movement of the jaws and then upwardly to effect a separating movement of the jaws, means for locking the rod in its downwardly moved position with capacity for a limited upward movement to permit of a corresponding separation of the jaws during justification, means independent of the line for effecting such limited upward movement of the rod, a pair of cams movable with the rod and adjustable with reference thereto to control the extent of its upward movement after locking, means for rendering one of said cams active and the other inactive as required, and means for adjusting the active cam in varying the upward movement of the rod. 100
- 20 31. In a slug casting machine, the combination of a pair of line clamping jaws relatively adjustable to accommodate lines of different measure, means for closing the jaws upon a composed line and thereafter separating them for a limited distance to permit justification, and means controlled by the initially adjusted position of the jaws to determine the extent of their separation for lines of a given measure. 105
- 25 32. In a slug casting machine, the combination of a pair of line clamping jaws relatively adjustable to accommodate lines of different measure, means for closing the jaws upon a composed line and thereafter separating them for a limited distance to permit justification, means controlled by the initially adjusted position of the jaws to determine the extent of their separation for lines of a given measure, and further means controlled by the closing-in movement of the jaws to reduce the extent of their separation for lines of less than 110
- 30 the given measure. 115
- 35 33. In a slug casting machine, the combination of a pair of line clamping jaws, means for closing the jaws upon a composed line for quadding or centering and thereafter separating the jaws for a limited distance to permit justification, means for conditioning the machine for quadding or centering, and means for effecting a uniform separation of the jaws under a given setting whether quadding or centering. 120
- 40 34. In a slug casting machine, the combination of a pair of line clamping jaws, means for closing the jaws upon a composed line for quadding or centering and thereafter separating the jaws for a limited distance to permit justification, means for conditioning the machine for quadding or centering, means for effecting a uniform separation of the jaws under a given setting whether quadding or centering, and means controlled by said conditioning means for insuring a uniform separation of the jaws under a given setting whether quadding or centering. 125
